UNITED STATES PATENT OFFICE.

ROBERT W. LEE, OF BROOKLYN, NEW YORK, ASSIGNOR OF ONE-FOURTH TO FREDERICK C. PITCHER AND ONE-HALF TO ALBERT G. STILLWELL, BOTH OF BROOKLYN, NEW YORK, AND ONE-FOURTH TO CARL S. STERN, OF NEW YORK, N. Y.

ROPE-CLAMP.

1,250,599.

Specification of Letters Patent. Patented Dec. 18, 1917.

Application filed October 31, 1914. Serial No. 869,608.

To all whom it may concern:

Be it known that I, ROBERT W. LEE, a citizen of the United States, and resident of the borough of Brooklyn, in the city and State 5 of New York, have invented a new and useful Improvement in Rope-Clamps, of which the following is a specification.

This invention relates to rope clamps, with the object in view of providing a device of 10 this character which will freely permit the passage of a flexible cord when drawn through in one direction, but automatically clamp the cord against movement when attempted to be drawn in the reverse direction.

Another object is to provide means for manually operating the pulley so as to permit the cord to move in the inhibited direction.

20 A further object is to provide such a device which is very simple in its construction, and which contains certain improvements in its form and construction and in the arrangement of parts, whereby the above 25 named and other objects may be effectively carried out.

A practical embodiment of the invention is represented in the accompanying drawings, in which,

30 Figure 1 represents a side elevation of the whole device with the cord clamped therein.

Fig. 2 represents a front elevation of the same.

35 Fig. 3 represents a side elevation reverse to that shown in Fig. 1.

Fig. 4 represents a horizontal section taken in the plane of the line A—A of Fig. 2, looking in the direction of the arrows.

40 Fig. 5 represents a vertical section taken in the plane of the line B—B of Fig. 1, looking in the direction of the arrows, and

Fig. 6 represents a vertical section taken in the plane of the line B—B, Fig. 1, looking in the direction opposite to the arrows showing the movable member in position to release the cord.

The device consists of an outer member which has a cylindrical portion, denoted by 50 1, provided with a correspondingly shaped bore therethrough. This cylindrical portion

is completely circular in form at its two faces, but has its wall intermediate the two faces cut away for about three-quarters of its circumference, thus leaving the wall 55 solid from face to face for only one-quarter of its circumference, as clearly shown at 2, in Fig. 5. These cut away portions are denoted by 3 and 4. At one side of the cylindrical portion 1, this outer member is projected in reduced cylindrical form as indicated at 5, which reduced portion, at its extremity takes the form of a hollow circular rim 6. The other end of the outer member has an eye 7 secured thereto or integral 60 therewith, in order to provide means for conveniently supporting the clamp as a whole in the desired location and position.

The device also comprises an inner member 8, which consists of a cylindrical body 70 portion adapted to fit within the bore of the member 1, so as to be oscillatable in a rotary direction therewithin. This body portion of the inner member 8 is completely circular at its two faces, but has its wall 75 intermediate its faces cut away for about half its circumference, thereby leaving only about half of the wall solid, as shown at 9, Fig. 5. A handle 10 is provided at one side of the inner member 8 for manual operation 80 thereof.

It will be noted that the reduced portion 5 of the outer member projects slightly to one side of the cylindrical portion 1, so that the rim 6 lies to one side of the cylindrical 85 portion of the inner member 8, or, in other words, is inset therefrom, instead of in a direct line therewith. The solid wall 2 of the cylindrical portion 1 of the outer member may be provided with a groove or lip 90 11 at the edge thereof, for the purpose of accommodating the flexible cord, as will be hereinafter described.

When the parts are assembled with the inner member within the outer member as 95 described, a flexible cord 12 may be passed through the openings in the walls of the cylindrical portions 1 and 8 of the outer and inner members, one end of the cord being also passed through the rim 6. The end 100 of the cord which is selected to pass through the rim 6, is the one which comes from that

side of the inner member 8 which is farthest out of line with the rim 6, which end is shown at the left in Figs. 2 and 5 and at the right in Fig. 6. This leading of the 5 cord 12 through the guide rim 6, causes it to bend sharply about the edge of the wall 9 of the inner member 8, as clearly shown in Fig. 5.

In operation, it will be seen that when the 10 device is secured by means of its eye 7, in any desired position, tension upon the end of the cord which passes through the guide rim 6 will rotate the inner member 8 so as to cause the edge of its wall 9 to move away 15 from the lower edge of the wall 2 of the outer member, as shown in Fig. 6, thereby leaving a free passage through the device for the cord 12, and hence permitting the latter to be pulled therethrough at will. As 20 soon, however, as tension is exerted upon the other end of the cord, thereby starting it in the reverse direction, the inner member 8 will be correspondingly rotated, thus moving the edge of its wall 9 toward the near 25 edge of the wall 2 and almost immediately clamping the cord between these two side edges, as clearly shown in Fig. 5. In this position the cord will be resting in the groove or lip 11. In case it is desired to 30 permit the cord to slip slightly in the inhibited direction while tension is thereon, the inner member 8 may be rotated by the handle 10 so as to momentarily release the cord; but as soon as the operator lets go 35 of the handle 10, the tension on the cord will automatically cause the inner member 8 to rotate in the opposite direction, thereby again clamping the cord as previously described.

40 The leading of one end of the cord through the rim 6, so as to cause it to bend sharply about the clamping edge of the wall 9 of the inner member, aids in the security of the hold and also insures that a reverse 45 strain upon the cord will at once rotate the inner member so as to quickly release the cord.

It will be understood that various changes 50 may be resorted to in the form, construction and arrangement of the several parts without departing from the spirit and scope of my invention, and hence I do not intend to be limited to the specific details herein described except as they may be set forth in 55 the claims.

What I claim is:

1. A device of the character described comprising an outer member having a cylindrical bore therein and a hollow cylindrical 60 guide rim, the wall of said member being cut away for substantially three quarters the circumference of the bore to form radial edges, a hollow cylindrical inner member rotatably fitted in said bore, the wall of said

inner member being cut away for substantially one half of its circumference to form radial edges to coact with aforesaid radial edges of the outer member, the said cutaway portions being disposed so that a flexible cord may be passed transversely across the axis of rotation of said inner member and between the radial edges of both members and one end of said cord passed through said rim, whereby tension on the other end of the cord will rotate the inner member so as to cause the cord to be gripped between the radial edges of the inner and outer members and tension on the cord passing through the rim will rotate the inner member so as to release the cord and permit it to be freely drawn through the clamp. 65 70 75 80

2. A device of the character described comprising an outer member having a cylindrical bore therein and a hollow cylindrical guide rim inset therefrom, the wall of the 85 said member being cut away for substantially three quarters the circumference of the bore to form radial edges, a hollow cylindrical inner member rotatably fitted in said bore, the wall of said inner member being cut away for substantially one half of its circumference to form radial edges to coact with aforesaid radial edges of the outer member, the said cutaway portions being disposed so that a flexible cord may be 90 95 100 105 passed transversely across the axis of rotation of said inner member and between the radial edges of both members and one end of said cord passed through said rim, whereby tension on the other end of the cord will rotate the inner member so as to cause the cord to be gripped between the radial edges of the inner and outer members and tension on the cord passing through the rim will rotate the inner member so as to release the cord and permit it to be freely drawn through the clamp. 110

3. A device of the character described comprising an outer member having a cylindrical bore therein and a hollow cylindrical 115 guide rim inset therefrom, the wall of said member being cut away for substantially three quarters the circumference of the bore to form radial edges, a hollow cylindrical inner member rotatably fitted in said bore, the wall of said inner member being cut away for substantially one half of its circumference to form radial edges to coact with aforesaid radial edges of the outer member, the said cutaway portions being 120 125 disposed so that a flexible cord may be passed transversely across the axis of rotation of said inner member and between the radial edges of both members and one end of said cord passed through said rim, whereby tension on the other end of the cord will rotate the inner member so as to cause the cord to be gripped between the radial edges

of the inner and outer members and tension on the cord passing through the rim will rotate the inner member so as to release the cord and permit it to be freely drawn 5 through the clamp, and means formed integral with the wall of the outer member and diametrically opposite said guide rim for supporting the clamp.

In testimony, that I claim the foregoing as my invention, I have signed my name in 10 presence of two witnesses, this twenty eighth day of October 1914.

ROBERT W. LEE.
